UNITED STATES PATENT OFFICE.

ALFRED M. PARKS, OF PHILADELPHIA, PENNSYLVANIA.

DESIGN FOR A CAMPAIGN-BADGE.

No. 39,540.

Specification for Design.

Patented Sept. 15, 1908.

Application filed June 29, 1908. Serial No. 441,039. Term of patent 3½ years.

To all whom it may concern:

Be it known that I, ALFRED M. PARKS, a citizen of the United States, residing at No. 6387 Woodbine avenue, in the city of Philadelphia, county of Philadelphia, and State of Pennsylvania, have invented a new, original, and ornamental Design for Campaign-Badges, of which the following is a specification, reference being had to the accompanying drawing, forming part thereof.

My campaign badge comprises a real or

artificial buckeye 1, and a ribbon engaging and arranged in relation to the buckeye, as shown.

I claim:

The ornamental design for a campaign badge, as shown and described.

ALFRED M. PARKS.
